GLASS-LINED CONTAINERS FOR CORROSIVE SUBSTANCES

Percy E. Knudsen, Pittsburgh, Pa., assignor to Pittsburgh Plate Glass Company, Allegheny County, Pa., a corporation of Pennsylvania

Application October 19, 1943, Serial No. 506,792

5 Claims.

(Cl. 206—2)

The present invention relates to the construction of containers for liquids, e. g., corrosive substances, such as pickling acids, cleaning solutions, plating baths, or for other materials of like nature, and it has particular relation to the provision of containers of the foregoing type in which a shell of wood, metal, concrete, or the like is lined by relatively heavy plates of glass providing a surface which is highly resistant to attack.

One object is to provide a container, the contents of which can easily be inspected.

A second object is to provide improved means for spacing the lining and the outer shell of such containers.

These and other objects will be apparent from consideration of the following specification and claims.

It has heretofore been proposed to form containers for various types of acids and solutions by setting plates of glass, preferably tempered, inside a container in somewhat spaced relation with respect to the walls of the container, in order to provide a lining and then to fill the space between the plates and the shell with a resistant plastic substance, such as high melting asphalt or plasticized sulfur, poured in while molten and allowed to set to a solid state.

The present invention contemplates as one feature the provision of sight holes or inspection windows for such containers in which the continuous plates of glass constituting the lining function as a transparent closure medium permitting the free passage of light into the contents of the tank.

As a further feature of the invention involves the provision of adjustment screws operable exteriorly of the tank for securing the glass plates constituting the tank lining in spaced relation with respect to the walls.

For a better understanding of the invention reference may now be had to the accompanying drawings in which like numerals refer to like parts throughout and in which Fig. 1 is an elevational view illustrating a tank constructed in accordance with the provisions of the present invention; Fig. 2 is a fragmentary sectional view taken substantially upon the line II—II of Fig. 1; Fig. 3 is a fragmentary sectional view taken substantially upon the line III—III of Fig. 1 and illustrating the construction of a corner of the tank.

In the embodiment of the invention shown a wooden shell 10 includes side walls of relatively heavy planks or boards 11, which are rabbeted 5

together as indicated at 12 in Fig. 3 to provide a corner structure. The corners are further reinforced and secured together by vertical bars 13 of wood secured to the boards 11 by means of screws 14. The side walls may also be reinforced by means of horizontal rods or bolts 16 and vertical bolts 17 which, at their extremities, are provided with nuts 18 countersunk as indicated at 19 into the wood. The nuts of the horizontal bolts are covered by the bars 13, while the upper nuts of the vertical rods are covered by coping bars 20.

The bottom of the shell is also formed of wooden planks 21 which, at their extremities, rest upon bars 22 of wood or the like. The lower nuts of the bolts 17 are countersunk in these latter bars.

The lining of the tank, as shown in Fig. 3, includes thin plates 23 of glass bearing against the inner surface of the wooden shell and plates 24 spaced therefrom, and preferably of relatively heavy plate glass, which should be tempered in order to render it resistant to heat shock. The vertical edges of the latter plates are beveled as indicated at 25 and their upper edges are secured 20 in grooves in coping bars 20 so that they can not fall inwardly. The space between the thin plates and the heavy plates is filled with a mastic or plastic composition 26, preferably of high melting asphalt or a plasticized sulfur, which in general 25 is highly resistant to chemical attack and also serves to transmit stresses from the lining plates to the outer shell as well as sealing all joints between plates.

It is to be observed that the plates 23 and 24 are held in suitably spaced relation with respect to each other by means of round pointed set screws 27, which are threaded through nuts 28, countersunk in openings 29 in the inner face of the walls of the shell. Said screws include indentations 27a for a screw-driver by means of which screws may be adjusted to obtain accurate spacing of the plates and to hold the plates from rattling during or prior to the operation of pouring the heated asphalt 26. The rear extremities 40 of the set screws may be protected by means of plugs 30 of wood or the like, and the points may have caps 30a of lead to protect them.

The lining of the bottom portion of the tank may include slightly sloped edge sections 31, that comprises plates 32 and 33, which rest upon beveled or wedge-shaped blocks or bars 34 upon the bottom boards 21 and are spaced by small sections 35 of glass. The space between the plates is filled with a mastic introduced while hot and fluid in a casting operation. The bottom also

includes a horizontal central section 36 having a drain opening 37 formed therein, which opening registers with a drain structure 38.

An inspection window in the tank constructed in accordance with the provision of the invention includes an opening 41, which is but a small section of the tank wall, formed in the tank at an appropriate point, but which does not extend through the lining plate 24. The opening is shown as being rectangular with a horizontal lower edge and is surrounded by a frame 42 of wood or the like. Wooden bars 43 may be inserted between the inner and outer sheets of glass in order to provide spacers. It is to be noted that the body of the thermosetting, e. g., "Bakelite," plastic 44 is disposed about the margins of the spacer members 43, in order to prevent the possibility of molten asphalt from contacting with the wood of the members. This resin is applied while still plastic and adhesive. It is baked to 20 thermoset stage, after the spacers and the plates are assembled.

As shown in dotted line in Fig. 1, the spacer bars 43 constitute flattened isosceles triangles so that the lower edge of the bar along the lower edge of the opening is sloped upwardly approximately from its mid portion respectively to the right and left of the opening whereby to admit of the escape of imprisoned air laterally and upwardly at opposite ends of the bar from under 25 the lower edges of the bars as the molten plastic is poured into the space between the outer shell and the inner lining. Screws 46 secure the frame to the spacer bars 43 and also screws 47 function further to secure the frame to the edges of the 30 opening.

Under some conditions there might be a possibility of breakage of the liner plate 24, which would permit the escape of the contents through the opening in the tank wall. In order to safeguard against such occurrence a safety plate 48 is provided. This plate at its margins rests against the frame 42, and it may be locked in place by means of a second frame 49 of wood or the like, which is secured in place to horizontal reinforcing bars 51 and vertical bars 52 by means of screws 53. These reinforcing bars are held in place by means of screws 54 threaded into the walls of the shell and function further to reinforce the edges of the opening. As best shown in Fig. 1, the horizontal bars 51 are of such length that they can be mortised into the vertical corner bars 13. The vertical bars 52 are also mortised into bars 51.

The construction of the tank herein shown is substantially self-evident. The wooden shell is first built up, after which the thin plates 23 are disposed in the shell in contact with the wood. The heavy inner plates 24 are disposed in position and the set-screws 27 are then adjusted to obtain the desired spacing and to insure contact between the face of the glass plates and the points and screws. The plastic, such as asphalt of high melting point, is fused at a temperature at which it is highly fluid and is then poured into position. It serves to bond the glass plates in position and to insure uniform bearing surface for the backs of the glass plates 24. Sometimes the wooden shell 10 may be replaced by a shell of iron or concrete. The tank may be round, square, or have any number of sides.

As many observation windows as may be desired may be built into a tank. For example, a second one 56 may be inserted opposite the first and a light 57 may be placed back of it to facilitate

observation. In some cases quantitative end points in chemical reactions can thus be observed with considerable accuracy.

The forms of the invention herein shown and described are to be considered merely as by way of example. It will be apparent to those skilled in the art that numerous modifications may be made therein without departure from the spirit of the invention or the scope of the appended 10 claims.

What I claim is:

1. A container structure comprising an outer reinforcing shell and an inner lining of glass plates, the plates of the lining being spaced from the shell, said outer shell having an inspection opening formed therein, the margins of the opening being closed by a frame, the inner edges of which bear against the outer face of the glass lining and a packing of impermeable plastic in the space between the lining and the shell.

2. A corrosion-resistant container for liquids comprising an outer reinforcing shell and a lining of glass plates disposed in the shell and being spaced inwardly from the shell, the lining being spaced from the surface of the shell, the space between the lining and the shell being filled with fusible mastic, the mastic and the shell being formed with an inspection opening therein; the lining of glass plates being continuous over the opening, and a safety covering of glass sealed in the opening and being spaced outwardly from the lining.

3. A container structure comprising an outer reinforcing shell and a lining of glass plates spaced therefrom, said outer shell having a pair of inspection openings formed therein upon opposed sides thereof, the margins of the openings being closed by frames and the space between the walls of the shell and the glass plates being filled with mastic.

4. A container structure comprising an outer reinforcing shell and a lining of glass plates spaced inwardly from the shell, said outer shell having an inspection opening formed therein with a horizontal lower edge, the margins of the opening being closed by a frame the inner edges of which bear against the outer faces of the glass lining and a packing of impermeable fusible mastic between the lining and the shell and spacer elements comprising bars disposed between the shell and the glass plates along the edges of the opening, the bar along the lower edge being of the lower edge of the bar along the lower edge of the opening being sloped upwardly approximately from its midportion respectively to the right and left of the opening to facilitate the escape of bubbles during pouring operations in the introduction of the mastic into the space.

5. A container structure comprising an outer reinforcing shell of planks, a lining of glass plates therein, said outer shell being formed with a square opening with two edges in horizontal position and two vertical edges, the margins of the opening being closed by a frame, the inner edges of which bear against the outer faces of the glass lining, a packing of impermeable mastic between the lining and the shell, vertical corner bars upon the shell on the outside thereof and reinforcing bars for the horizontal edges of the opening and having the ends secured to said corner bars and vertical bars reinforcing vertical edges of the opening and being secured to the first-mentioned bars.
